SUPPORT FOR A SCOOP

Harold R. Anderson, 7950 Wesley Drive,
Minneapolis, Minn. 55427

Filed June 13, 1973, Ser. No. 369,712

Term of patent 14 years

Int. Cl. D6—04

U.S. Cl. D67—3 B

FIG. 1

FIG. 2

FIG. 3

FIG. 5

FIG. 4

FIG. 6

FIG. 1 is a perspective view of a support for a scoop showing my new design, wherein the broken line discloses a cabinet, its contents, and the scoop are shown for illustrative purposes only;

FIG. 2 is a top perspective view illustrating the front and side panels of the support for a scoop;

FIG. 3 is a top plan view of the support for a scoop;

FIG. 4 is a rear view of the support for a scoop;

FIG. 5 is a side elevational view of the support for a scoop, with the opposite side being identical to the side shown; and

FIG. 6 is a bottom plan view of the support for a scoop.

I claim:
The ornamental design for a support for a scoop, as shown and described.
